UNITED STATES PATENT OFFICE.

ROBERT SCHULZ, OF MILWAUKEE, WISCONSIN.

WINDOW-SCREEN.

1,387,947.

Specification of Letters Patent. Patented Aug. 16, 1921.

Application filed June 15, 1920. Serial No. 389,071.

To all whom it may concern:

Be it known that I, ROBERT SCHULZ, a citizen of the United States, and resident of Milwaukee, in the county of Milwaukee and 5 State of Wisconsin, have invented certain new and useful Improvements in Window-Screens; and I do hereby declare that the following is a full, clear, and exact description thereof.

10 My invention relates to new and useful improvements in screens for use in connection with building openings such as windows and employing sliding sashes or other similar closures.

15 The principal object of this invention is to provide a screen structure which can be automatically moved into position to cover a window opening when the sash is slid to open position.

20 An additional object of the invention is to provide a structure of this character which can be normally housed within a compartment formed in one of the building walls adjacent one of the sides of the window or 25 like frame. A further object of the invention is to provide a finishing strip for a screen structure of this character which, while normally housed within the screen sash compartment, is automatically moved 30 outwardly to an operative position when the screen is shifted to an extended position.

Still another object of this invention is to 35 provide a finishing strip of this character which together with its operating means can be completely carried by the screen sash.

With these and other objects in view, the invention resides in the novel features of construction, combination and arrangement of parts which will be hereinafter more particularly described and claimed.

In the accompanying drawings,

Figure 1 represents an elevational view of a window frame and the adjacent parts of a building showing the relation of my invention thereto.

Fig. 2 is an enlarged elevational view of certain parts shown in Fig. 1 and with other parts broken away and in section.

Fig. 3 is a horizontal sectional view taken 50 substantially on the plane of the line 3—3 of Figs. 1 and 2 and,

Fig. 4 is a vertical sectional view on the plane of the line 4—4 of Fig. 1.

Referring more particularly to these 55 drawings, the reference character 1 denotes

a window frame having the usual sill 2 and sash grooves 3 in which upper and lower window sashes 4 and 5 respectively are vertically slidable. In carrying out the present invention, the building wall W below the 60 sill 2 is provided with a screen sash compartment 6, ingress and egress for this compartment being had through a slot 7 formed in said sill 2.

A screen sash 8 is normally located within 65 the compartment said sash consisting of a pair of like frames 9 between which a rectangle of screen material 10 is clamped. In other words the edges of the screen material are disposed between the two frames 9 70 which are then secured together by fastening elements such as the nuts and bolts 11. (For instance see Fig. 3). Together the two frames 9 form a sash which is of a thickness 75 substantially equal to the width of the slot 7 and corresponds to the thickness of the lower window sash 5 as will be evident from Fig. 4.

Thus the screen sash 8 may readily slide 80 in the sash grooves 3 of the window sash 5 as well as in grooves provided in the opposite walls of the compartment 6. Inasmuch as it is desirable that the screen sash 8 be moved simultaneously with the window sash 5, means is provided for detachably connecting the upper edge of the sash 8 to the lower edge of the sash 5. In other words, the window sash 5 carries a latch 12 having fingers 13 for detachable connection with a latch plate 14 on the sash 8. Even though 90 the two sashes 5 and 8 are normally moved vertically together, it is obvious that they may be individually slid to their different positions when the latch 12 is not in use.

Ordinarily the sash 5 is not raised to such 95 an extent as to expose the bottom of the screen sash 8, therefore a pair of finishing strips 15 are provided for use when the screen sash is raised; these finishing strips, when in operative position, being located one on 100 each side of the screen covering 10 adjacent the sill 2. Thus that portion of the screen covering 10 close to said sill is protected as would be the case if the screen sash was completely extended out of its compartment. 105 When the screen sash is housed within the compartment 6, the finishing strips are likewise located therein, and under normal conditions are capable only of a limited outward movement, they being restrained by spring 110

pressed detents 16 which project from their opposite surfaces and engage the opposite edges of the slot 7.

These finishing strips automatically follow the uppermost side of the screen sash 9 when the same is moved outwardly by reason of the counter-balance weights 17. In other words, the opposite ends of the strips 15 have tongues 18 which slide in grooves 19 in the corresponding sash frames 9 and have the ends of sash cords 20 connected thereto. These cords 20 are trained around pulleys 21, one of which is located at each upper corner of each of the frames 9, and connected with the counter-balance weights 17, these weights being housed within channels 22 formed in the vertical sides of said frames 9.

In the use of the invention, assuming that it is desired to simultaneously raise the lower sash 5 and elevate the screen sash to close the resultant window opening, the latch 12 is operated to connect the sashes 5 and 8 together, whereupon as the former is raised to a predetermined extent, the screen sash is correspondingly raised. As soon as the upper side thereof is raised above the sill 2, the finishing strips 15 will be extended outwardly of the compartment 6 until the detents 16 are engaged as shown in Fig. 4, this raising of the strips being automatically accomplished by the counter-balance weights 17. Should it be necessary to entirely remove the screen sash 8 from the compartment 6, the finishing strips 15 are forcibly raised to retract the detents 16 and cause them to slide through the slot 7. On the downward movement of the window sash 5, the screen sash will be lowered to a similar extent, but the finishing strips 15 will remain stationary until engaged by the upper side of said sash 8.

I claim:

1. The combination with a window or similar frame having an opening at one side providing an entrance way into a sash compartment, of a sash movable into and out of the compartment, and a movable finishing strip extending across the sash in the side of the frame adjacent said opening whereby to simulate a portion of said sash.

2. The combination with a window or similar frame having an opening at one side providing an entrance way into a sash compartment, of a sash movable into and out of the compartment, a movable finishing strip extending across the sash, said strip being housed within said compartment when the sash is retracted, and means for moving the strip exteriorly of the compartment to a position adjacent the opening thereof when the sash is positioned outwardly of its compartment.

3. The combination with a window or similar frame having an opening at one side providing an entrance way into a sash compartment, of a sash movable into and out of the compartment, a movable finishing strip extending across the sash, said strip being housed within said compartment when the sash is retracted, means for moving the strip exteriorly of the compartment when the sash is positioned outwardly of its compartment, means normally limiting said outward movement of the strip to a position adjacent said opening in the frame side, said limiting means being operable to permit further movement of the strip when it is desired to move the sash entirely from the frame.

4. The combination with a window or similar frame having an opening in one side providing an entrance way into a sash compartment, and a main sash movable in the frame, of an auxiliary sash movable into and out of the compartment by movement of the main sash, means for detachably connecting the two sashes together, and a finishing strip normally disposed in said compartment and movable outwardly thereof to a position adjacent said opening in the frame side when the auxiliary sash is moved outwardly.

5. The combination with a window or similar frame having an opening in one side providing an entrance way into a sash compartment, and a main sash movable in the frame, of an auxiliary sash movable into and out of the compartment by movement of the main sash, means for detachably connecting the two sashes together, a finishing strip slidable in the frame of the auxiliary sash and normally disposed in said compartment, and means for moving the strip outwardly a limited extent when the auxiliary sash is moved out of the compartment.

6. The combination with a window or similar frame having an opening in one side providing an entrance way into a sash compartment, and a main sash movable in the frame, of an auxiliary sash movable into and out of the compartment by movement of the main sash, means for detachably connecting the two sashes together, a finishing strip slidable in the frame of the auxiliary sash and normally disposed in said compartment, and means located in the auxiliary sash for moving the strip outwardly a limited extent when the auxiliary sash is moved out of the compartment.

In testimony that I claim the foregoing I have hereunto set my hand at Milwaukee, in the county of Milwaukee and State of Wisconsin.

ROBERT SCHULZ.
